UNITED STATES PATENT OFFICE.

LEVI MADISON SHARPS, OF LAKE VIEW, OREGON; WILLIAM M. SHARPS
ADMINISTRATOR OF SAID LEVI MADISON SHARPS, DECEASED.

WATER-WHEEL.

SPECIFICATION forming part of Letters Patent No. 443,151, dated December 23, 1890.

Application filed May 11, 1889. Serial No. 310,391. (No model.)

To all whom it may concern:

Be it known that I, LEVI MADISON SHARPS, of Lake View, in the county of Lake and State of Oregon, have invented a new and Improved 5 Water-Wheel, of which the following is a full, clear, and exact description.

The invention relates to water-wheels, such as shown and described in Letters Patent No. 126,752, granted to me May 14, 1872.

10 The object of the invention is to provide a new and improved water-wheel which is simple and durable in construction and very effective in operation.

15 The invention consists in certain parts and details and combinations of the same, as will be hereinafter described, and then pointed out in the claim.

20 Reference is to be had to the accompanying drawings, forming a part of this specification, in which similar letters of reference indicate corresponding parts in all the figures.

25 Figure 1 is a plan view of the improvement. Fig. 2 is a sectional side elevation of the same on the line *xx* of Fig. 1. Fig. 3 is a sectional plan view of the same on the line *yy* of Fig. 2. Fig. 4 is an inverted plan view of the apparatus, and Fig. 5 is an enlarged sectional detail view on the line *yy* of Fig. 1.

30 The improved water-wheel A is provided with a circular bed-plate B, having in its center on top a step or pivot C. To the under side of the bed-plate B are secured the radial arms D, projecting beyond the edge of the bed-plate and supporting the vertical annular rim E, carrying on top a ring F, fastened 35 to the spider G, through which passes loosely in the usual manner the main driving-shaft H, supporting the wheel I, which is located above the bed-plate B inside of the annular 40 rim E.

The wheel I is provided with a spider J, fastened on the shaft H and mounted to turn on the step or pivot C of the bed-plate B. On the outer ends of the arms of the spider J 45 are secured the buckets K, which are similar in shape and construction to the buckets shown in the patent above referred to. On the insides of the buckets are held the gates L, arranged in a circle and adapted to be 50 opened and closed so as to permit the water

to flow to the buckets K and to shut it off from the same.

Each of the gates L is secured on a shaft N, having its lower bearings in a disk O, held above the spider J and supported on a sleeve 55 O', secured to the bridge G. The upper bearings of the shafts N are in the stationary ring F, and on the upper end of each shaft is secured a lever P, extending outward and provided near its outer end with a slot P', 60 into which extends a pin Q, secured on a ring R, mounted to turn on the top plate F. On part of the periphery of the ring R is formed the segment of a gear-wheel S, meshing into a pinion T, secured on a short shaft U, 65 stepped on the top plate F, and adapted to be operated by a suitable key inserted from above.

In the bed-plate B is formed an aperture B', adapted to be covered by a slide V, held 70 in suitable guideways on the under side of the bed-plate B, as is plainly shown in Fig. 4. The aperture B' serves to remove the sand accumulating on the top of the bed-plate B.

The operation is as follows: In the position 75 shown in Fig. 3 the gates L are open, and the water flowing into the opening of the top ring F passes by the gates L to the buckets K, whereby the wheel I is turned and the power transmitted by the shaft H to suitable ma- 80 chinery. When the operator desires to stop the wheel I, he turns the shaft U so that the pinion T is rotated and the ring R is turned slightly, whereby the levers P are carried along, so that the shafts N are turned in their 85 bearings and the gates L are closed. The wa- 90 ter is now held inside of the wheel and cannot escape through the buckets K. The water from the buckets passes downward to the radial arms D and out of the water-wheel. 90

Having thus fully described my invention, I claim as new and desire to secure by Letters Patent—

A water-wheel consisting in the outer sta- 95 tionary cylindrical casing E, the top ring F, fixedly secured on top of the casing, the bot- 100 tom disk B, having a series of arms D connecting it with the lower end of the casing, the annular series of buckets K, rotating under the top rim within the casing, the rotary 100

spider J, supporting the said buckets and supported centrally on the step C, the shaft II, connected at its lower end with the hub of the spider, the stationary disk O above the 5 spider, the annular series of gates L, suspended inside of the series of buckets and provided with vertical axes journaled in ring F and disk O and having arms P, slotted at their outer ends, a ring R, rotating on top of 10 ring F and having vertical pins entering the

slots of the arms P, and means for rotating the ring R, the circular central space within the series of gates being open at the top for the column of water, substantially as set forth.

LEVI MADISON SHARPS.
